SAFETY PILOT CONTROL

Henry F. Schoenfeld, Cleveland, and Raymond J. Smithisler, Kirtland Township, Lake County, Ohio, assignors, by mesne assignments, to The Ajax Thermostatic Controls Company, Gates Mills, Ohio, a corporation of Ohio

Application September 22, 1948, Serial No. 50,628

10 Claims. (Cl. 137—65)

1

This invention relates to improved controls for gas burners, particularly controls embodying simple, reliable heat-responsive units of the type hereinafter described.

In the operation of gas burners, there is an element of danger arising out of the possibility that, following interruption of the flow of gas in the system or failure of the pilot burner to continue to function for some other reason, gas may be admitted to and discharged unburned by the main burner. In some types of burners, provision is made for automatically cutting off the supply of gas to the main burner but no provision is made for cutting off the passage of gas to the pilot burner, thus permitting leakage of the unburned gas from the pilot burner. In an effort to remedy these deficiencies, controls have been proposed in the past that would cut off the supply of gas to both the main and pilot burners; however, such controls have proven to be complicated, unreliable, or both.

The present invention makes possible, and has for its principal object to provide, a simple, reliable control for gas burners that operates to cut off the supply of gas to both main and pilot burners in the event that some abnormal condition inhibits operation of the main burner. A further object is to provide a control that may without difficulty be installed, actuated, and adjusted to different conditions of operation. Another object is to provide a control in which operation of the actuating mechanism is easily initiated from the exterior of the device. Still another object is to provide a simple, reliable heat-responsive unit for controls of these and other kinds that may be installed, adjusted and, if necessary, replaced, all with a minimum of effort.

The invention is illustrated in the accompanying drawing, in which:

Figure 1 is a sectional plan, with parts in elevation, of a control constituting a preferred embodiment of the invention;

Figure 2 is a vertical section, with parts in elevation, along line 2—2 of Figure 1;

Figure 3 is a vertical section, with parts in elevation, along line 3—3 of Figure 1;

Figure 4 is a transverse vertical section, with parts in elevation, along line 4—4 of Figure 1;

Figure 5 is a detail, on an enlarged scale, of the sealing assembly appearing in elevation in Figure 4;

Figure 6 is a diagrammatic perspective showing the actuating mechanism of Figures 1, 3 and 4 in the first ("off") position;

2

Figure 7 is a similar view showing the same actuating mechanism in the second ("pilot") position;

Figure 8 is a similar view showing the same actuating mechanism in the third ("on") position;

Figure 9 is a side view of the outer cam in the position illustrated in perspective in Figure 8;

Figure 10 illustrates the control of Figures 1 to 4 as employed with a gas burner used for heating water;

Figures 11, 12 and 13 show, in sectional plan, a modified control within the purview of the invention and illustrate the actuating mechanism thereof in the "off," "pilot" and "on" positions, respectively;

Figure 14 is a transverse vertical section on line 14—14 of Figure 11; and

Figure 15 is a side view of the open link forming part of the actuating mechanism of the modified control of Figures 11 to 14, inclusive.

The control illustrated in Figures 1 to 9, inclusive, is characterized, among other things, by a body or block having two separate passageways therethrough. In each of said passageways is located a spring-pressed check valve biased toward closed position. A single actuator serves both check valves, unseating them seriatim when the control is put into operation. In normal operation, the actuator is held by a thermally-operated detent in a position in which both valves are unseated. Upon the development of a condition which inhibits continued operation of the main burner, the actuator functions to permit the check valves to seat, the seating being seriatim but in reverse order as compared with the order in which the valves are unseated.

Referring now to Figures 3 and 4, body 1, which preferably takes the form of a block machined from bar stock or a casting, is provided with a wide threaded inlet 2 admitting gas from the supply system. On the opposite side of body 1 is a narrow threaded outlet 3 through which the gas so admitted passes to the main burner. Between inlet 2 and outlet 3 is a smooth connecting bore 4, which is narrower than inlet 2 and of substantially the same diameter as outlet 3. At the base of inlet 2 is an annular shoulder 5 which serves as a valve seat for main valve 6. The latter consists, in addition to the valve body, of an O-ring packing 7, a hollow stud 8, which, if desired, may be solid, spring centering means 9, and a coil spring 10 which abuts against and is placed under compression by the inner end of a coupling member 11 which serves as a cap or retainer for the valve assembly.

As shown in Figures 1, 2 and 4, body 1 is further provided with a second threaded inlet 15, a smooth connecting bore 16 of smaller diameter, the latter constituting an extension of inlet 15, and a communicating cross bore 17 drilled from the exterior of body 1 at right angles to inlet 15 and connecting bore 16. The outer end of cross bore 17 is closed by a suitable plug. Between inlet 15 and connecting bore 16 is an annular shoulder 18 which serves as a valve seat for pilot valve 19. The latter is generally similar to main valve 6 in that it is provided with an O-ring packing 20, is biased toward seating position by a coil spring 21, and is retained in place by a coupling member 22 which is similar to, but smaller than, coupling member 11. Mounted for movement with but on the opposite side of pilot valve 19 is a plunger 23 which extends through a suitable opening in the wall 24 separating connecting bore 16 from connecting bore 4. As indicated in Figures 1 and 4, plunger 23 projects well into connecting bore 4. Surrounding plunger 23 is the sealing assembly 25, shown in detail in Figure 5, which comprises an O-ring packing 26, an overlying washer 27 and a coil spring 28 which forces the O-ring packing 26 into sealing contact with plunger 23 and wall 24.

The purpose of inlet 15, connecting bore 16 and cross bore 17, is to provide a passageway admitting gas to pilot burner tube 33.

Figures 2 and 4 illustrate the manner in which an orifice of the conventional type may be inserted in body 1 between cross bore 17 and pilot burner tube 33. A threaded bore 30 extending from the exterior of body 1 to a point in proximity to cross bore 17 provides access to a second threaded bore 31 of smaller diameter. The latter communicates with a smooth connecting bore 32 which extends through body 1 in prolongation of threaded bores 30 and 31. Pilot burner tube 33 having openings 34 is brazed or screwed in place in connecting bore 32 at a point spaced from orifice 35. Between orifice 35 and the inner end of pilot burner tube 33 is an air opening 37 which permits air to mix with the gas passing through orifice 35 into pilot burner tube 33. Access to orifice 31 may be had by removing orifice cap 36, which serves to seal bore 30 against the escape of gas when the control is in operation.

The actuating mechanism or actuator for main valve 6 and pilot valve 19 is located in body 1 in the relationship shown in Figures 1 and 3.

A transverse bore 40 communicating with bore 4 in the first of the two above-described passageways extends from one side to the other of body 1. At opposite ends of bore 40 two bushings 41 are mounted, as by brazing, in gas-tight relation to the ends of bore 40. Within bushings 41 is located a shaft 42 which is so mounted as to permit it to have a considerable degree of rotary movement and which projects beyond the sides of body 1. Rigidly affixed to shaft 42 at a point midway of bore 40 is an inner cam 43, shown also in Figure 4. On opposite sides of inner cam 43 and abutting bushings 41 are sealing assemblies 44 generally similar to sealing assembly 25. On the same side of body 1 as pilot burner tube 33 is an outer or locking cam 45 which is rigidly affixed to the projecting end of shaft 42. On the opposite end of shaft 42 is an actuating knob or dial 46 having indicia thereon which serve to disclose the position of the actuator at any given time. Within knob 46 is a return spring 47 of the torsion type, the ends of which are fixed to knob 46 and body 1.

As shown in Figures 1 and 3, a post or rod 50

parallels pilot burner tube 33, being mounted in body 1 in such manner as to preclude the possibility of movement other than the hereinafter described movement of its free end. Preferably, post 50 is solid and fabricated from type 430 stainless steel having a co-efficient of expansion of .0000065; however, it may be of hollow construction and, if desired, of some other material having a higher or lower co-efficient of expansion. Adjacent post 50 is a generally L-shaped primary element 51 which has its outer end 52 at the end of the long leg thereof shaped to conform to and welded onto post 50 at the outer end thereof. Primary element 51 has a relatively high degree of expansibility, being preferably of type 437 stainless steel with a co-efficient of expansion of .0000095; however, any other suitable material with a co-efficient of expansion of the same order of magnitude may be used instead; e. g., type 421 stainless steel.

The short leg 53 of L-shaped primary element 51 extends at right angles to the long leg thereof in a position to overlie outer cam 45. It is provided with a longitudinally extending slot (not shown) through which extend two screws 59 which serve to attach adjusting strip 57 to short leg 53. Adjusting strip 57 is coextensive as to width with short leg 53 of primary element 51 and is mounted for adjustment lengthwise of short leg 53 by suitable manipulation of the screws 59. At one end of adjusting strip 57 is a tang 58, struck up from strip 57, which serves as a cam stop for outer cam 45 in a manner hereinafter to be described.

Welded to primary element 51 at the unsupported inner end thereof, but at a point short of the point at which short leg 53 extends therefrom, is a secondary element 54 which, like post 50, preferably is, but need not necessarily be, of type 430 stainless steel with a co-efficient of expansion of .0000065. Therefore, as compared with primary element 51, secondary element 54 is characterized by limited expansibility. At the end of secondary element 54 opposite the unsupported inner end thereof is an L-shaped bracket 55 one shank of which is brazed, welded or otherwise affixed to secondary element 54 and another shank of which, extending at right angles, is received and welded in place in a slot 56 milled in post 50 at a point intermediate the supported and unsupported ends of primary element 51.

Post 50, primary element 51 and secondary element 54 are so related, by being mounted in the manner above described, as to permit of considerable transverse movement but little lengthwise movement of either element. As the flame from pilot burner tube 33 strikes the near side of the free end of post 50, the supported end of primary element 51, and such parts (if any) of secondary element 54 as are exposed to it, primary element 51 tends to lengthen as a result of its relatively high coefficient of expansion. However, because of the relatively low coefficient of expansion of secondary element 54, which places a limit on effective lengthwise expansion of primary element 51, the latter tends to bow toward post 50, an action which has the net effect of imparting a generally clockwise or upward movement to the short leg 53 of primary element 51 and the unsupported end of secondary element 54 as seen in Figure 1.

This transverse movement of the parts is somewhat accentuated by the limited expansion occurring in post 50 as a result of localized heating near the free end thereof on the side next

to pilot burner tube 33. The side of the free end of post 50 near the pilot burner tube reaches a higher temperature than the opposite side; thus, the side near the pilot burner tube expands more than the opposite side. As a result, the free end of post 50 tends to bend away from pilot burner tube 33 in a generally clockwise or downward direction as seen in Figure 1, thus imparting to the supported outer end of primary element 51 a turning force which has the effect of accentuating the generally clockwise or upward movement of short leg 53. Such movement of short leg 53 produces corresponding movement in strip 57 and tang or cam stop 58.

By modifying the materials and proportions of the several parts, different operating characteristics, particularly different operating times, can be developed in the heat-responsive unit. For example, the limited expansion of the free end of post 50 can be enhanced by using a type of stainless steel or some other suitable material having a coefficient of expansion higher than the characterizing type 430 stainless steel. Similarly, by varying the difference in length between primary element 51 and secondary element 54, it is possible to increase or decrease the sensitivity of the heat-responsive unit and therefore of the control as a whole. With due regard to these and similar factors, the present invention thus makes it possible to provide a control which, unlike the controls of the prior art, is capable of reliable operation even at very high ambient temperatures.

Referring now to Figure 9, outer cam 45, which receives tang 58, takes the form of a shallow disk-like member that may be cast as shown or machined from an originally circular blank. Of its four quadrants, only two adjacent quadrants, A and B, remain largely or entirely intact. Of a third quadrant C, nothing remains except a quarter-circle 60 near the center. The fourth quadrant D contains a guiding slot 62 terminating in an inwardly extending notch or recess 63 located at the inner end of slot 62 but formed in quadrant A rather than in quadrant D. The inner wall of guiding slot 62 is defined by a quarter circle 61 which adjoins and is of the same radius as the quarter circle 60 remaining at the center of quadrant C.

On the far side of guiding slot 62 is an arcuate member 65, located largely in quadrant D, of which the inner edge 64 forms the outer wall of guiding slot 62. The radially extending end face 67 of arcuate member 65 cooperates with tang 58 in a manner to be described, as does also the radially extending face 66 located at the point where quadrant B and quadrant C adjoin. Together with the recess 63 at the inner end of guiding slot 62, the semi-circular portion 60 is adapted to serve as part of a detent mechanism which includes tang 58.

As shown in diagrammatic fashion in Figures 6, 7 and 8, the actuator for main valve 6 and pilot valve 19 consists essentially of shaft 42, inner cam 43, outer cam 45 and knob 46. As indicated in Figure 6, in the first ("off") position, valves 6 and 19 are seated on their respective valve seats 5 and 18. In this position, the lobe of inner cam 43 extends downward out of contact with stud 8 on main valve 6 and out of contact with plunger 23 on pilot valve 19. Tang 58 on adjusting strip 57 is in contact with radially extending face 66 formed by outer cam 45 at the point where quadrants B and C adjoin. This is the relationship of parts, more particularly the relationship of the

actuator to main valve 6 and pilot valve 19, when the control unit is first installed in the main burner.

When it is desired to place the control in operation, knob 46 is rotated counterclockwise through an arc of 90°, which brings the lobe of inner cam 43 into contact with plunger 23 of pilot valve 19 and thus forces the latter away from its seat on annular shoulder 18. At the same time, outer cam 45, being rigidly affixed to shaft 42, is rotated through an arc of 90°, which serves to bring radial end face 67 on arcuate member 65 into contact with tang 58. This is the second ("pilot") position and is illustrated in Figure 7.

With the parts in this relation to each other, gas escaping through openings 34 in pilot burner tube 33 can be ignited. In this position, spring 47 tends to return the parts to their original position, so that continuing effort must be exercised through knob 46 to keep pilot valve 19 unseated.

As the free end of post 50 and the supported end of primary element 51 heat up under the influence of the pilot flame, short leg 53 of primary element 51 moves laterally as already described, carrying with it adjusting strip 57 and tang 58. With knob 46 held in the second ("pilot") position, short leg 53, adjusting strip 57 and tang 58 move inward across radial end face 67 of arcuate member 65 into registry with guiding slot 62. This action, which normally requires from fifteen to thirty seconds for its completion, permits the actuator to be rotated through a further arc of 90° by continued counterclockwise movement of knob 46. At this point the actuating mechanism arrives at the relationship indicated in Figure 8, illustrating the third ("on") position.

In this position, the lobe on inner cam 43 is in contact with both plunger 23 on pilot valve 19 and stud 8 on main valve 6, so that both pilot valve 19 and main valve 6 are now unseated. The flow of gas past main valve 6 which results permits the flame emanating from openings 34 in pilot burner tube 33 to ignite the gas escaping from the main burner. In the meanwhile, continued lateral movement of short leg 53 of primary element 51, adjusting strip 57 and tang 58 brings the latter into recess 63 and, by detent action, prevents return spring 47 from restoring the parts to their original position.

Upon the development of an abnormal condition which inhibits continued operation of the main burner, by which is meant that both the flame at the main burner and that emanating from openings 34 in pilot burner tube 33 have been inadvertently extinguished, primary element 51 tends to contract, reversing the lateral travel of short leg 53, adjusting strip 57, and tang 58. Movement of tang 58 toward post 50 in consequence of this contraction of primary element 51 results in disengagement of tang 58 and outer cam 45 at the inner end of guiding slot 62. This permits progressive return of the actuator, including inner cam 43, to its original position, with consequent seating of main valve 6 and pilot valve 19 in that order. Tang 58 rides on surfaces 61 and 60 of the inner semi-circular portion of outer cam 45 until it finally abuts radial face 66, at which point the parts are again in their original position.

The control illustrated in Figures 1 to 9, inclusive, may be installed in the system as indicated in Figure 10. So installed, a bracket 70 holds body 1 in operating position. Conduit 71 supplies gas for pilot burner tube 33 to body 1.

Conduit 72 supplies gas for main burner 74 to body 1. Conduit 73 supplies gas from body 1 to main burner 74. The control as so incorporated in the system is in addition to the control provided by the usual thermostat acting in response to changes in temperature in the water or other medium being heated by main burner 74.

A modified control is illustrated in Figures 11 to 15, inclusive. Such control, like that illustrated in Figures 1 to 9, inclusive, is characterized, among other things, by two separate passageways through a body or block, a spring-pressed check valve, biased toward closed position, in each of said passageways, and actuating mechanism, operable manually from the exterior of the control, for unseating the valves seriatim. Cooperating with the actuating mechanism and serving to hold both valves in unseated position is a heat-responsive unit similar to that illustrated in Figures 1 to 4 but lacking the angularly extending portion comprising short leg 53 of primary element 51. In other respects, the modified heat-responsive unit comprising post 150, primary element 151 and secondary element 154 is much the same as the heat-responsive unit illustrated in Figures 6 to 8, inclusive.

As indicated in Figures 11 to 13, inclusive, the modified control comprises a body 101 machined or otherwise formed from bar stock or a casting. It is provided with a wide threaded inlet 102 receiving gas from conduit 72 (Figure 10), a narrow threaded outlet 103 permitting gas so received to travel thence to the main burner, and a smooth connecting bore 104. Inlet 102 and outlet 103 extend at right angles to each other, being coupled together by connecting bore 104. At the junction of connecting bore 104 and inlet 102 is an annular shoulder 105 serving as a valve seat for main valve 106. The latter consists, in addition to the valve body, of O-ring packing 107, hollow stud 108, spring centering means 109, and coil spring 110, all of which are retained in place by action of coupling member 111 on spring 110.

At the opposite side of body 101 is an opening in which is received a bushing 112 brazed in gas-tight relation in body 101. Through such bushing extends a pin 113, one end of which is received in stud 108 on main valve 106 and the other end of which projects beyond the body 101. Located between stud 108 and bushing 112 is a sealing assembly 114 generally similar to the sealing assembly shown in Figure 5.

A second passageway through body 101 is formed by threaded inlet 115, which receives gas from conduit 71 for the pilot burner flame; by a smooth connecting bore 116, relatively narrow as compared with inlet 115; by a cross bore 117 drilled from the exterior of body 101 and plugged at its outer end; by a threaded bore 118 parallel to connecting bore 116, and by a smooth outlet bore 119 in which is mounted pilot burner tube 33, the latter being brazed or screwed in place. Located approximately at the center of body 101 is orifice 120, the same being inserted and removed through threaded bore 118. The latter is sealed against escape of gas by orifice cap 121. Extending transversely through body 101 at a point in proximity to the discharge side of orifice 120 is air inlet 122, shown in Figure 14.

Located at the junction of inlet 115 and connecting bore 116 is an annular shoulder 123 serving as a valve seat for pilot valve 124. The

latter is generally similar to main valve 106, being characterized by an O-ring packing 125, a coil spring 126 biasing the pilot valve to closed position, and means taking the form of coupling member 127 for placing spring 126 under compression. On the opposite side of body 101 is a bushing 128 brazed in position in gas-tight relation in body 101. Through bushing 128 extends a pin 129, the inner end of which, surrounded by a sealing assembly 130 generally similar to the sealing assembly shown in Figure 5, abuts against valve 124.

Rigidly mounted on the projecting outer end of pin 129 is a button 131 by which force may be applied to pilot valve 124 to unseat the same against the action of coil spring 126.

Overlying button 131 is an open link 132, shown also in Figure 15, by which main valve 106 may be actuated in similar manner. Near its open end, link 132 surrounds pilot burner tube 33, one branch 135 of the link overlying button 131 and the other branch 136 extending parallel to branch 135. At its other end, link 132 has a slot 137 in which is received a bolt-like member 133 fastened to pin 113. Cooperating with bolt-like member 133 and serving to clamp link 132 in place between them is a nut 134. Adjustment of link 132 toward and from pilot burner tube 33 is made possible by slot 137, bolt-like member 133 and nut 134.

As shown in Figures 11 to 13, inclusive, primary element 151 and secondary element 154 are squared off at their unsupported ends as indicated at 138, this to provide a detent adapted to engage the flat outer face of branch 136 of link 132.

With the parts in the position indicated in Figure 11; that is to say, with the parts in the cold position, the control is installed much as contemplated by Figure 10. When it is in order to initiate operation of the burner, force is applied manually to depress button 131, which results in immediate unseating of pilot valve 124. This action permits gas to enter inlet 115, connecting bore 116, cross bore 117, threaded bore 118, outlet bore 119, and pilot burner tube 33. The flow of gas thus established permits lighting of the pilot flame. Localized heating of post 150 and the supported end of expansible element 151 results in growth of primary element 151 with consequent transverse movement of squared-off end 138. At this point, the parts are in the position indicated in Figure 12, the main valve being closed and the pilot valve 124 being open.

As squared-off end 138 approaches branch 136 of link 132, it becomes necessary to apply manual force to, and thereby to depress, link 132, which action serves to unseat main valve 106. Because branch 135 of link 132 overlies button 131, it is then no longer necessary to continue to apply manual force to button 131: the same end is accomplished by the application of manual force to link 132. Unseating of main valve 106, with attendant inward movement of the pin 113 and link 132, permits squared-off end 138 of primary element 151 and secondary element 152 to come into engagement with and ride upon the flat outer face of branch 136 of link 132. This state of affairs is indicated in Figure 12 and continues until there is an interruption in the operation of the main burner.

If, however, an abnormal condition develops to inhibit operation of the burner, including the pilot flame, primary element 151 contracts, with resulting reversal of the original movement. The resulting inward travel of squared-off end 138

of primary element 151 and secondary element 154 disengages link 132, permitting main valve 126 and pilot valve 124 to seat. Such seating takes place substantially simultaneously. Thus the parts return to the cold position indicated in Figure 11, precluding all flow of gas until such time as manual actuation is again employed to restore the system to operation.

Advantages of the invention as expressed in each of the two above-described embodiments include the possibility of installation of the control in almost any position, a feature which follows from the use of spring-pressed check valves rather than valves which depend upon the action of gravity. The controls illustrated in Figures 1 to 9 and Figures 11 to 14 are easy to manufacture, simple to assemble, and reliable in operation. They lend themselves to many uses other than the indicated use in connection with the heating of water; in fact, certain parts thereof such as the elements of the heat responsive unit, i. e., post 59 or 150, primary element 51 or 151, and secondary element 54 or 154, as the case may be, lend themselves to installation in controls of other types. A high degree of reliability, coupled with flexibility, characterizes both the heat-responsive units and the controls themselves.

Numerous changes may be made without departing from the inventive concept and it is therefore desired that the invention should be accorded the scope contemplated in the appended claims, which are intended to define whatever features of patentable novelty reside in the invention.

We claim:

1. A control for a gas burner comprising a valve body provided with a valve alternately permitting and preventing flow through the valve body; a post rigidly mounted on the valve body; a relatively expansible element of elongated form one end of which is supported from the post and the other end of which is unsupported, such unsupported end being located in proximity to but spaced from the valve body; a relatively inexpansible element attached to the expansible element at a plurality of widely separated points one of which is near the unsupported end of the expansible element; and, mechanically connected to the valve, a manually movable latching member located in the space between the valve body and the expansible element, the unsupported end of the expansible element having a coacting portion serving as a detent for said manually movable latching member.

2. A gas burner control as in claim 1 in which the manually movable latching member takes the form of a flat-surfaced link.

3. A gas burner control as in claim 2 in which the link is adjustable toward and from the detent.

4. A control for a gas burner comprising a valve body provided with a valve alternately permitting and preventing flow through the valve body; a post rigidly mounted on the valve body; a relatively expansible element of elongated form one end of which is supported from the post and the other end of which is unsupported, such unsupported end being located in proximity to but

spaced from the valve body; a relatively inexpressible element attached to the expansible element at a plurality of widely separated points one of which is near the unsupported end of the expansible element; and, mechanically connected to the valve, a manually movable cam member located in the space between the valve body and the expansible element, the unsupported end of the expansible element having a coacting portion serving as a detent for said manually movable cam member.

5. A gas burner control as in claim 4 in which the unsupported end of the expansible element includes a part that acts as a cam stop.

6. A gas burner control as in claim 5 in which the cam includes a slot receiving that part of the expansible element that acts as the cam stop.

7. A control for a gas burner comprising a valve body provided with a plurality of functionally independent valves, each of said valves alternately permitting and preventing flow through the valve body; a post rigidly mounted on the valve body; a relatively expansible element of elongated form one end of which is supported from the post and the other end of which is unsupported, such unsupported end being located in proximity to but spaced from the valve body; a relatively inexpressible element attached to the expansible element at a plurality of widely separated points one of which is near the unsupported end of the expansible element; and, mechanically connected to each of the valves in the valve body, a manually movable latching member located in the space between the valve body and the expansible element, the unsupported end of the expansible element having a coacting portion serving as a detent for said manually movable latching member.

8. A gas burner control as in claim 7 characterized by the presence of mechanical means for seating the valves substantially simultaneously.

9. A gas burner control as in claim 7 characterized by the presence of mechanical means for seating the valves serially.

10. A gas burner control as in claim 7 characterized by the presence of mechanical means for unseating the valves serially.

HENRY F. SCHOENFELD.
